UNITED STATES PATENT OFFICE.

WILLIAM A. HOLDINGHAUSEN, OF CLOVIS, NEW MEXICO.

STEAM BOILER.

Application filed February 9, 1924. Serial No. 691,717.

The object of this invention is to provide an efficient steam boiler especially adapted for use upon motor vehicles. The invention seeks to provide a boiler which will occupy very little room and which will be of such construction that the water therein will be quickly converted into steam. The invention also provides a boiler of sectional type in which a broken or damaged section 10 may be very easily and quickly removed and a new section substituted therefor so that the owner of the boiler will not be deprived of the use of the same for any considerable period. Incidentally the invention provides means for removing sediment and provides simple means for carrying off the smoke and other products of combustion. A casing for the boiler is also provided which will be of such construction that loose 20 or open joints are eliminated and the heat will be confined to play about the water tubes so as to economically convert the water into steam. The invention is illustrated in the accompanying drawings and 25 will be hereinafter fully set forth.

In the drawings:

Figure 1 is a side elevation, partly broken away, of my improved boiler showing the same installed in the hood of an automobile; 30 Fig. 2 is a transverse section on the line 2—2 of Fig. 1;

Fig. 3 is a top plan view with the cover removed; and

Fig. 4 is a detail section on the line 4—4 35 of Fig. 2.

In carrying out my invention, I provide a casing which may be supported in any convenient manner upon the frame of the automobile and arranged under the hood 1 of the same. This casing consists of base or 40 supporting members 2 constructed in their upper edges with sockets, as indicated at 3, to receive the reduced tongues or tenons 4 upon the lower edges of side plates 5. The 45 casing also includes front and back plates 6, the side edges of which are recessed, as shown at 7, to accommodate the edges of the side plates and asbestos or other packing, as indicated at 8, may be employed to close the 50 joints between the side plates and the front and back plates and also to seat the tenons 4 in the sockets 3. A cover 9 is also provided, said cover having depending flanges 10 at all its sides which fit closely against the outer faces of the side and back and 55 front plates, thereby holding the upper

edges of the said side plates and the back and front plates closely together so that air-tight engagement is effected and dissipation and loss of heat prevented.

Arranged transversely in the casing are 60 a series of boiler sections each of which

comprises vertical tubular members 11 and 12 disposed adjacent the side plates of the casing, a lower tubular member or header 13 connecting the lower ends of the said side

tubular members and an upper tubular member or header 14 which also connects and establishes communication between the

said side tubular members, the upper header 14 being arranged obliquely or inclined to the horizontal, as clearly shown in Fig. 2.

Extending between the headers 13 and 14 are water tubes 15 which are open at their

upper and lower ends and establish communication between the said headers, as

clearly shown in Fig. 2, and extending through each of said water tubes and

through the headers 13 and 14 are flues 16,

the upper and lower ends of which are like- 70

wise open, as clearly shown in Fig. 2. The

ends of the flues are welded or otherwise se- 75

cure in the bottom wall of the header 13 and the top wall of the header 14, and a

burner of any preferred type is disposed

below the several sections to play directly

upon the lower headers 13 and create a cir- 80

culation of hot air through the several flues

16 and around the water tubes so that the

column of water between each tube and the

flue extending through said tube will be ex- 85

posed to heat from opposite sides and, there- 90

fore, very quickly raised in temperature.

Extending along one side of the casing is a

water supply pipe 17 which is connected at

intervals by branches 18 with the respective

side tubes 11, a cut-off valve 19 being pro- 95

vided in each branch between the supply

pipe 17 and the casing, and the branch in- 100

cluding a union coupling 20 so that, if re- 105

pairs be needed, any particular section may

be cut out by merely closing the proper cut- 110

off valve 19 and disengaging the coupling

20, as will be readily understood. At the

opposite side of the casing is a mud drum 21

having connection with the several sections

through pipes 22 and provided at both ends

with blow-off valves 23. The drum, as

shown most clearly in Fig. 2, is located be- 115

low the series of sections constituting the

main body of the boiler so that the water

will naturally flow into the drum. The

boiler, however, is subjected to the influence of heat from the burner over such a wide area that the water is kept at a high temperature and impurities therein are not apt to adhere to the several tubes or heads, but, inasmuch as the water is in constant circulation or agitation, the impurities will be drawn through the several pipes 22 into the drum 21 and may be removed therefrom at intervals by blowing or washing. Union couplings 50 are provided in the pipes 22, said couplings and the unions 20 being all located outside the casing so as to be easily accessible and so that any leaks may be readily detected and repaired.

The pipes 18 are of copper tubing and relatively small in diameter and they are coiled, as shown at 51, to accommodate expansion, contraction and movement in the sections due to road use of the car.

The several tubes 12 extend above the headers 14, as shown most clearly in Fig. 2, and pipes 24 extend from the upper ends of these tubes across the casing below the top of the same to a steam dome or drum 25 which is supported above the side tubes 11, the drum being disposed below the pipes 24, as shown. From the under side of the drum, small drip tubes or nozzles 26 depend into the side tubes 11 at the ends of the boiler so that any water of condensation which may tend to accumulate in the drum will be returned to the boiler sections to be again heated and vaporized. While a drip tube 26 may be provided for each section of the boiler, ordinarily they will be provided at the end sections only in order to permit maximum flexibility in the boiler. Extending inwardly from the drum is a short pipe 27 connecting the said steam drum with a header or drum 28 which is disposed parallel with the steam drum above the several boiler sections and extending preferably the full length of the boiler. This drum 28 forms one member of a superheater, being connected with a second similar parallel collecting drum 29 by a plurality of U-shaped superheating pipes 30 disposed between the boiler sections and extending downwardly to the plane of the several lower headers 13. From the rear end of the collecting drum 29, a take-off pipe 31 passes to the throttle of the engine whereby the steam will be caused to drive the engine and the speed of the latter may be controlled. While only two superheater pipes 30 are shown, it will be understood that they may be provided in such numbers that one of them will be arranged between each two boiler sections. It will be noted, upon reference to Fig. 2, that the turns in the superheater pipes are as nearly as possible right angles so that the steam will be changed in direction as often as possible and the highest efficiency of the superheater obtained. The drums 28 and

29 are suspended from the pipes 24 by hanger clamps 52.

Supported by the back plate of the casing is a smoke conduit 32 which may be carried under the body of the vehicle to 70 discharge the smoke and products of combustion in rear thereof in a manner similar to that in which the exhaust from internal combustion engines is now commonly discharged. The upper end of the smoke conduit 32 opens into a collecting chamber 33 disposed at the back of the casing and preferably of a cup or trough-like formation having its open upper side substantially equal to the width of the boiler. It will be 80 understood that the motion of the traveling vehicle will create a strong draft through this collecting chamber and smoke conduit which will serve to effectually withdraw all waste products of combustion so that the 85 deposit of soot and other foreign matter upon any of the water tubes or in the fire flues will be avoided and the boiler kept in efficient condition with very little attention.

As has been said, a burner is located below the several headers 13. This burner may be of any preferred type and is not illustrated in the accompanying drawings inasmuch as the particular form of burner constitutes no part of my present invention. The heat 95 given off by the burner will rise through the several fire tubes 16 and through the spaces between the several water tubes 15 so that it will play upon the several columns of water at the centers thereof through the fire flues and also upon the outside thereof through the water tubes. As a result, the water will be very quickly raised in temperature and steam rapidly formed. As the water is heated, it, of course, expands and it may rise through the several tubes to 100 the header 14. Inasmuch as this header is disposed obliquely or at an angle to the horizontal, the water is not apt to rise in all the tubes so as to enter the header 14 through 105 the entire length thereof and, consequently, there will always be a space at the higher end of the said header and at the upper end of the side tube 12 free of water and through which the steam may readily pass 110 to the steam dome and thence to the superheaters. As the water rises in the tube 15 next the side tube 11, for instance, it will enter the header 14 and, if it continues to 115 expand and increase in height, it will overflow into the adjacent water tube 15 before it will pass any great distance along the header. As the water reaches a high temperature, it will jump from the tubes 15 and 120 strike against the top wall of the header 14 and flow down the side and back into tube 11 or carry forward through the header to the upper end thereof over the tube 12 where the water will drop from the steam 125 and return to the water level while the steam 130

will pass on to the steam dome. A circulation of water from the tubes 11 and 12 to the tubes 15 is thus set up so that the water rotates violently and the formation of hot spots is avoided. It will be noted that unions 53 are provided in the pipes 24. When removal of a boiler section becomes necessary, the unions 20, 50 and 53 of the section are disconnected and the section may then be easily withdrawn. The structure is compact, may be easily installed and is especially adapted for use upon motor vehicles.

Having thus described the invention, I claim:

1. A steam boiler comprising a plurality of independent sections each consisting of a lower header, an upper header inclined to the horizontal from one end of the section to the other end thereof, vertical water tubes connecting the ends of the headers, intermediate vertical water tubes connecting the headers between the ends thereof, fire flues extending through the last-mentioned water tubes and the headers, a steam drum disposed above the lower ends of the upper headers, independent connections between the drum and the higher ends of said headers, and superheaters connected with the drum and suspended vertically between the several sections.

2. A steam boiler comprising a plurality of independent sections each consisting of a lower header, an upper header inclined to the horizontal from one end of the section to the other end thereof, vertical water tubes connecting the ends of the headers, intermediate water tubes connecting the headers between the first-mentioned water tubes, fire flues extending through the last-mentioned water tubes and the headers, a steam drum disposed above the lower ends of the upper headers, connections between the drum and the higher ends of said headers, superheaters connected with the drum and disposed between the several sections,

and drip members depending from the drum into the lower ends of the upper headers.

3. A steam boiler comprising a plurality of independent sections arranged side by side and each consisting of a lower header, an upper header inclined to the horizontal from end to end of the section, vertical water tubes connecting the ends of the headers, intermediate water tubes connecting the headers between the ends thereof, fire flues passing through the last-mentioned water tubes and the headers, a steam drum disposed above the lower ends of the upper headers, connections between the drum and the higher ends of said headers, a second drum disposed over the several sections, connections between said second drum and the steam drum, a collecting drum also disposed over the several sections, U-shaped superheater pipes arranged between the several adjacent sections and forming communication between the collecting drum and the said second drum, means for carrying off steam from the collecting drum, and means for independently supplying water to the several sections.

4. A steam boiler comprising a plurality of independent sections arranged side by side and each consisting of upper and lower headers, water tubes connecting the ends of the headers, intermediate water tubes connecting the headers between the ends thereof, fire flues passing through the intermediate water tubes and through the headers, U-shaped superheater pipes disposed vertically between adjacent sections, connections between the upper headers of the several sections and one end of the respective superheater pipes, and means above the sections connected with the other ends of the superheater pipes to deliver the steam at the point of use.

In testimony whereof I affix my signature.

WILLIAM A. HOLDINGHAUSEN. [L.S.]
